CLAIM

The ornamental design for a dental appliance connecting arm, as shown and described.

DESCRIPTION

FIG. 1 is a perspective view of a dental appliance connecting arm;

FIG. 2 is a front view of the dental appliance connecting arm of FIG. 1;

FIG. 3 is a top view of the dental appliance connecting arm of FIG. 1;

FIG. 4 is a bottom view of the dental appliance connecting arm of FIG. 1;

FIG. 5 is a left side view of the dental appliance connecting arm of FIG. 1;

FIG. 6 is a right side view of the dental appliance connecting arm of FIG. 1;

FIG. 7 is a front view of the dental appliance connecting arm of FIG. 1 as used in a dental appliance in a closed position; and,

FIG. 8 is a front view of the dental appliance connecting arm of FIG. 1 as used in a dental appliance in an opened position. The broken lines shown in the figures depict environmental structure that form no part of the claimed design.
